UNITED STATES PATENT OFFICE.

JOSEPH W. HOLMES, OF NEWARK, NEW JERSEY.

LAST.

1,149,196.

Specification of Letters Patent. Patented Aug. 10, 1915.

Application filed December 23, 1914. Serial No. 378,828.

To all whom it may concern:

Be it known that I, JOSEPH W. HOLMES, a citizen of the United States, and a resident of Newark, county of Essex, and State of New Jersey, have invented certain new and useful Improvements in Lasts, of which the following is a specification.

My invention relates to lasts, and particularly to the provision of improved reinforcing means for the toe portions thereof.

In the making of shoes by modern machinery the lasts are subjected to extremely rough treatment, especially in the process of "pulling" the uppers, which are pulled and stretched in place on the last after the insole has been placed thereon by powerful machinery specially designed for this purpose, and which exerts great stretching and pulling stresses on the leather. As the parts of the upper are pulled and stretched into place they must be tacked through the insole to the last to hold them firmly in place as the stretching and pulling operation proceeds. When the toe of the last is at all slender, as in making shoes with pointed toes, the wood of the last into which these tacks are driven is subjected to rapid deterioration, particularly toward the extreme point of the last.

I have found that by inserting a reinforce of fiber in the toe of the last flush with the bottom thereof and extending to the extreme end or point thereof, the life of the last can be greatly prolonged, since the fiber is not chewed up by the tacks, as is the case with the wood, for it is not necessary to drive the tacks into the fiber to anything like the depth necessary with the wood in order to secure a sufficiently firm holding of the upper in place thereon as the work of stretching and pulling and tacking the upper into place progresses.

With the above and related objects in view, my invention consists in the parts, improvements and combinations herein set forth and claimed.

In the accompanying drawing forming a part of this specification, and wherein the same reference numerals are made use of to designate the same parts throughout, Figure 1 is a fragmentary side view of a last to which my invention is applied. Fig. 2 is a partial bottom plan view of the last shown in Fig. 1, and Fig. 3 is a cross-sectional view on the line 3—3 of Fig. 1.

The body of the last is designated by the numeral 10 and the insert of fiber by the numeral 11. The cut-out 12 for the insertion of the fiber insert 11 is preferably made with a slight under-cut 13 on its sides, and such sides are preferably substantially parallel to one another to enable the ready insertion of the insert 11. The fiber insert 11, which is flush with the bottom of the last and extends to the extreme toe end thereof, may be held in place by any convenient means, as by being cemented in place or by driving it tightly into the recess provided therefor, or it may be secured by one or more nails or similar holding means. A hole 14 is preferably provided in the insert 11 fairly close to the extreme point or toe of the last in order that the tack for holding the toe part of the insole may be driven into place in the wood of the last, it being desirable that such tack shall pass into the last for the greater part of its length so as not to be in the way during subsequent operations.

With the last formed in this manner the tacks for holding the upper in place as it is pulled and stretched and formed into shape at the extreme toe point of the last may be driven into the fiber insert 11 and, as already stated, it is possible to secure the necessary firm holding of this part of the upper by tacks without driving them into the fiber for any considerable length, as the power of the fiber for holding tacks is much greater than that of the wood, and furthermore, the fiber is not split or chewed up by the tacks being driven thereinto repeatedly as is the wood in the operation of lasting a large number of shoes one after another upon a single last.

A reinforce in accordance with the present invention is readily and cheaply made and is extremely effective in that it greatly prolongs the life of the last which, except for my improved reinforce, must be discarded after a short period of use, the life of the other parts of the last being much longer than that of the unreinforced wooden toe, the wooden toe when not reinforced being the most vulnerable part of the last and that which always wears out first and causes the last to be discarded or to be cut down for use in shoes having blunter toes.

Having thus described my invention, I claim:

A wooden last having a recess at its bottom extending to the toe end, and a reinforce of fiber secured in said recess flush with the bottom of the last and extending 5 to the toe of the last and provided with an opening therein through which the tack for holding the insole may be driven into the wood of the last, substantially as set forth

In testimony that I claim the foregoing, I have hereto set my hand, this 19th day of 10 December, 1914.

JOSEPH W. HOLMES.
